THE NORRIS PETERS CO., PHOTO-LITHO., WASHINGTON, D. C.

UNITED STATES PATENT OFFICE.

JAMES MILTON WAUGH, OF CHICAGO, ILLINOIS.

DRAFT-RIGGING FOR RAILWAY-CARS.

SPECIFICATION forming part of Letters Patent No. 690,684, dated January 7, 1902.

Application filed August 7, 1901. Serial No. 71,144. (No model.)

To all whom it may concern.

Be it known that I, JAMES MILTON WAUGH, of Chicago, in the county of Cook and State of Illinois, have invented certain new and useful Improvements in Draft-Rigging for Railway-Cars; and I do hereby declare that the following is a full, clear, and exact description thereof, reference being had to the accompanying drawings, and to the letters of reference marked thereon, which form a part of this specification.

This invention relates to coupling devices for railway-cars, and refers more especially to the connections between the draft-bars and the draft-sills, whereby a graduated cushioned resistance to the shocks occurring in coupling and due to variable strains in traction is obtained.

The present invention relates more specifically to that class of connecting devices of the character illustrated in my prior application for United States Letters Patent, Serial No. 60,685, filed May 17, 1901, wherein a coiled draw-bar spring is used in connection with spring follower-plates, which follower-plates engage at their end shoulders on the draft-sills and intermediate endwise-sliding abutment-plates located between the ends of said follower-plates.

The invention consists in the matters hereinafter set forth, and more particularly pointed out in the appended claims.

In the drawings, Figure 1 is a horizontal section illustrating fragments of the draft-sills, the draft-irons attached to said sills, and the inner end of the draw-bar and its yoke, together with the draw-bar spring and the follower-plates at the ends of said yoke and the abutment-plates engaging the ends of said follower-plates. Fig. 2 is a vertical section of the parts shown in Fig. 1, the coiled spring and draw-bar spring being omitted. Fig. 3 is a transverse vertical section on line 3-3 of Fig. 2. Fig. 4 is a side elevation of one of the abutment-plates removed from its draft-iron.

Referring to the drawings, A A indicate the draft-sills of a car, and B the draw-bar, which is located centrally between the draft-sills and provided at its inner end with a yoke B', which is made in the usual or any preferred manner.

C designates a spiral coiled spring which is located between the arms of the yoke, being held from vertical displacement by said arms. At each end of the spring C, within the yoke, is located a set of transversely-arranged spring-steel follower-plates, the follower-plates constituting the set at the outer or forward end of said spring being indicated by the letters D D' and those at the inner or rear ends of said spring being indicated by the letters E E'.

F F designate draft-irons which are attached to the inner faces of the draft-sills and which are provided with forwardly and rearwardly facing shoulders f f', adapted for engagement therewith of the ends of the exterior curved follower-plates D E. On said draft-irons are mounted two horizontally-sliding abutment-plates G G, the ends of which form forwardly and rearwardly facing shoulders g g', opposed to the shoulders f f' on the draft-irons and adapted for contact with the ends of the inner straight follower-plates D' E'. The construction of said abutment-plates and the manner of mounting the same in the draft-irons constitute one feature of the present invention. The draft-irons are shown in the drawings as having the form of recessed or flanged plates, which are seated in mortises in the inner faces of the draft-sills A and are secured thereto by bolts in the manner shown. Said draft-irons are each provided with an upper horizontal flange f² and vertical ribs f³ f³, located near the ends thereof, and which form with said horizontal flange f² and a separate horizontal bottom plate or strap f⁴ recesses or sockets in which the ends of the follower-plates are located and within which the sliding abutment-plates G are inserted and adapted to slide. The inner faces of the vertical ribs f³ f³ constitute the inwardly-facing shoulders f f', hereinbefore referred to. The horizontal plates or straps f⁴ are removable secured to the lower margins of said plates, so as to form horizontal supporting-surfaces at the bottoms of said recesses or sockets, said plates f⁴ being adapted to support the ends of the follower-plates when the same are in place within the recesses or sockets of the draft-irons and by being removable enabling said follower-plates to be easily dropped out of their places when said plates f⁴ are de-

tached. The said bottom plates or straps f^4 are held in place by means of vertical bolts F' , which pass downwardly through the flange f^2 .

Provision is made for holding or confining 5 the sliding abutment-plates G in contact with the draft-irons while permitting free endwise movement of said plates, embracing an interlocking connection one between the margins of each plate and the draft-iron on which it 10 slides, whereby said plates will be held in position on the draft-irons without reliance upon the bottom plates or straps of said draft-irons. Said abutment-plates are herein shown as made of a width to fit within the space between the bottom plates and top flanges of the draft-irons and are provided with longitudinal slots $g^2 g^2$, through which pass horizontal pins $f^5 f^5$, which project inwardly from the draft-irons. As herein shown, said pins 15 have screw-threaded engagement with the irons and project through said slots a slight distance beyond the inner faces of the abutment-plates. If desired, however, the pins f^5 may be replaced by lugs integrally formed on 20 the draft-irons. The weights of the abutment-plates are supported by the bottom plates or straps f^4 of the draft-irons, the pins f^5 , and the extensions of the draft-irons, in which are formed the grooves in which the 25 lugs G' of the abutment-plate slide.

For confining the abutment-plates in contact with the draft-irons the said abutment-plates are provided at their upper margins with inwardly-directed longitudinal flanges G' , as 30 seen in Fig. 3. Said flanges occupy inwardly-opening guide-grooves formed in flange-like extensions F^2 on the upper margins of the draft-irons, as clearly shown in Figs. 3 and 4, said grooves being made of sufficient length 35 to permit the required travel of the abutment-plates. Said grooves in the extension F^2 and the lugs of the abutment-plates are so formed that the lugs can be introduced into the grooves only while said plates occupy an inclined position with the lower margins thereof 40 directed inwardly from the draft-irons and so that when said flanges have been entered into said grooves and the abutment-plates are seated against the inner faces of the draft-irons 45 the inner or extreme margins of the flanges G' will overhang the parts of the extensions F^2 below the guide-grooves therein, the extension forming horizontal bearings on which said extreme ends of the flanges rest and slide. Preferably and as herein shown the flange G' is 50 made of curved form and the projection F^2 of corresponding shape, this form of the flange being employed to facilitate the introduction and removal of the flange to and from the 55 guide-groove. In placing said abutment-plates on the draft-irons the flanges G' are inserted in the guide-grooves before the pins f^5 are inserted in place, and after the said abutment-plates are in place on the draft-irons the 60 pins are inserted through the slots g^2 into the openings in the draft-irons and screwed into place.

The lower margins of the abutment-plates are preferably arranged to have sliding engagement with the lower detachable plates or strips of the draft-irons, and in order to prevent lateral play or movement of the lower margins of said abutment-plates inward or away from the draft-irons the lower margins of the abutment-plates are provided with depending flanges G^2 , which extend downwardly 70 between the lower margins of the draft-irons and the adjacent edges of the bottom plates f^4 , as shown in Fig. 3. The abutment-plates are placed in engagement with the draft-irons before the bottom plates or straps f^4 are put in place, and after said straps are attached to the draft-irons the lower parts of the abutment-plates will be prevented from swinging inwardly and out of interlocking connections 75 with the pins f^5 . If by accident the bottom plates or straps f^4 of the draft-irons be detached and become lost, the abutment-plates will still be held in place by the interlocking engagement of the flanges G' with the longitudinal guide-grooves in the extensions F^2 of the draft-irons, and inasmuch as said abutment-plates cannot be detached from the draft-irons until said draft-irons are made to 80 assume an inwardly-inclined position and as 85 the coiled spring C prevents the lower parts of said plates from swinging inwardly said spring acts to prevent detachment of said lugs from the irons so long as said spring is in place.

As herein shown, the abutment-plates are recessed to give lightness, being provided with two horizontal or longitudinal ribs $g^3 g^4$ at the top and bottom edges thereof, two end ribs $g^5 g^5$, and an intermediate horizontal rib g^6 . 90 Said end ribs are made of considerable thickness to give the requisite strength to the plate and to form bearing-surfaces of suitable width for engagement with the ends of the follower-plates, and said intermediate ribs serve as 95 braces between said end ribs.

As before stated, the draft-irons fit within mortises in the inner faces of the draft-sills, and the ends of said draft-irons are provided with shoulders $f^6 f^6$, which bear against the 100 ends of the mortises in the draft-sills, and on the extremities of the plates are formed longitudinally-extending flanges F^3 , which are adapted to extend over the inner surfaces of the draft-sills adjacent to the ends of said 105 mortises. Said draft-irons are secured to the sills by suitably-applied bolts $H II$, as indicated by dotted lines in Fig. 1. The corners of said draft-irons at the bases of the flanges F^3 are rounded and engage rounded corners 110 of the mortises, this construction being similar to and made for the same purpose as shown in my prior application hereinbefore referred to.

In order to stiffen and strengthen the ends of the draft-irons and the flanges F^3 thereon, vertical ribs $f^7 f^7$ are shown as formed on said flanges parallel with the ribs f^3 , said ribs $f^3 f^7$ being cast integral with the upper flanges f^2 , which latter are extended outwardly to the 115

- outer ends of the flanges F⁸. Intermediate horizontal ribs f⁸ are arranged to extend from the ribs f³ to the ribs f⁷ and are continued in the form of triangular ribs f⁹, which extend 5 from said ribs f⁷ to the outer ends of the flanges F⁸. The bolts F', by which the lower plates or straps of the draft-irons are held in place, pass through the flanges f² and the horizontal ribs f⁸ between the ribs f³ and f⁷. 10 The bolts H are shown as inserted through the end portions of the draft-irons between the vertical ribs f³ f⁷ and are provided with heads which are seated in the bottoms of the recesses formed between said ribs, and in 15 order to afford room for the vertical bolts F' said bolt-heads are sunk into deep recesses formed to receive the same, as indicated in dotted lines in Fig. 1, the draft-irons being provided on their inner faces with inwardly-projecting bosses f¹⁰ to provide for said recesses and to give sufficient thickness to the metal at the points where the bolts pass 20 through the draft-irons.

Referring now more specifically to the construction and arrangement of the several follower-plates and the manner in which the same operate in connection with the sliding abutment-plates G, the same will be understood from the following: The drawings show each 25 set of follower-plates as consisting of four outer curved plates D E and three inner straight plates D' E'; but a greater or less number of plates may be used in each instance, according to the thickness of the plate and 30 other circumstances. The outer curved plates when the draw-bar is in its normal or central position bear at their ends against the forwardly and rearwardly facing shoulders f f' of the draft-irons. The intermediate 35 parts of the plates E bear at their convex sides against the inner end of the draw-bar yoke, while the intermediate portions of the plates D bear at their concave sides against the inner vertical part of the yoke B. The end 40 portions of the straight plates D' E' are adapted to bear against the ends of the sliding abutment-plates G upon movement of the draw-bar in either direction, while the intermediate portions of said plates bear against 45 the ends of the coiled draw-bar spring C. Said intermediate portions of the straight plates also bear against the convex or crowning faces of the curved plates D and E. In the normal positions of the parts the ends of 50 the straight follower-plates D' E' are out of contact with the ends of the abutment-plates G. The parts being in this position, when the draw-bar is forced toward the center of the car by the shock of coupling the end 55 thrust of the draw-bar is conveyed through the curved follower-plates D, the flat follower-plates D', the spiral spring C, the flat follower-plates E', and the curved follower-plates E to the forwardly or rearwardly facing shoulders f on the draft-irons. After the spiral 60 spring has been compressed to some extent the ends of the flat plates D' are brought into

contact with the adjacent ends of the sliding abutment-plates G, with the result of forcing or moving said plates endwise and bringing 70 the same into contact with the ends of the flat plates E' of the innermost set of plates. Thereafter upon continuous endwise movement of the abutment-plates said plates D' E' are flexed until they are brought into contact throughout their length with the curved plates D E. It will therefore be seen that during 75 the movement of the parts from the time the said plates D' E' are brought into contact with the sliding abutment-plates the movement of the draw-bar is resisted not only by the tension of the spring C, but also by the resistance afforded by the bending of said plates D' E'. If after the parts are brought into the position last mentioned inward 80 pressure on the draw-bar due to the shock of coupling is sufficient to still further bend the plate and is greater than will be absorbed by the resistance of the flat plates D' E' the curved plates E and said plates E', which 85 latter are at that time curved, will be flattened or straightened, while at the same time the plates D D' will remain in their curved form. At this time further inward movement 90 of the draw-bar will be resisted by the combined action of all of the plates which will be in contact with each other and will unitedly resist the inward stress on the draw-bar. When the several plates are thus brought into 95 contact with each other, they are intended to withstand the greatest inward pressure to which the draw-bar may be subjected, although by reason of the fact that a number 100 of plates are employed and that they still have some degree of resiliency or capacity for yielding under strain they will still present 105 to some degree a cushioned resistance to the inward movement of the draw-bar.

In the outward movement of the draw-bar, such as occurs when the train is starting or 110 under similar conditions, the movements before described will be reversed, the yoke in such case acting against the spring E and tending to bring the ends of the plates E' against the inner ends or shoulders g' of the 115 sliding abutment-plates.

From a comparison of the construction shown in this application with that shown in my said prior application, Serial No. 60,685, it will be seen that two sets of plates shown in 120 said prior application—to wit, the outermost straight plates—are omitted and that the end of the draw-bar and draw-bar yoke bear against the convex parts of the curved plates. As shown, however, the number of straight 125 plates omitted have been added, one to the straight set retained and the other to the curved set, whereby the combined strength of said follower-plates remains practically the same.

From the foregoing it will be obvious that the device as a whole affords a graduated resistance to sudden and severe shocks or strains acting on the draw-bar in either di- 130

rection. At the beginning of the inward movement of the draw-bar said movement is resisted by the draw-bar spring acting alone. When the sliding or movable abutment-plates 5 are brought into contact with the flat plates D' E', the movement of the draw-bar is resisted by said plates E' D' in addition to that of the spiral spring, and after said plates E' D' have been brought into contact with the 10 curved plates further movement will be resisted by the parts already in action and by a set of curved plates on that side of the draw-bar in the direction toward which the draw-bar is moving. It will also be noted that after 15 the abutment-plates G have carried the flat plates D' E' into contact with the convex sides of the curved plates upon a further continuation of the pressure the endwise movement of said abutment-plates tends to thrust the 20 ends of the innermost plates against the outer ends of the curved plates, and as the latter are then in contact with the shoulders on the draft-irons the said ends of the curved plates will be clamped or confined between the innermost plates and said shoulders, with the 25 result of producing a large amount of frictional resistance to the endwise movement of the end portions of the curved plate, and as the ends of said curved plates must necessarily move apart or spread endwise in the 30 straightening of the plates such frictional resistance to the outward movement of their ends will greatly increase the resistance to the straightening of said curved plate, and thus afford additional resistance to the endwise movement of the draw-bar.

From the above it will be seen that not only do the follower-plates arranged in connection with the sliding or endwise-moving 40 abutment-plates operate to afford a graduated spring resistance in opposition to the shock of coupling or the shock which occurs in starting the train, but a greatly-increased resistance is afforded at the time the draw-bar reaches the inward or outward limit of 45 its movement, and the final arrest of the movement of the draw-bar will be accompanied by a yielding resistance operating to gradually transmit to the draft-sills exceptionally powerful or severe shocks upon the 50 draw-bar.

I claim as my invention—

1. A draft-rigging comprising draft-sills, provided with inwardly-facing shoulders, a 55 draw-bar, a coiled draw-bar spring, spring follower-plates located one at each end of said draw-bar spring and adapted for engagement at their middle parts with the draw-bar spring and for contact at their ends with said shoulders, and endwise-sliding abutment-plates 60 located between the ends of said follower-plates, said abutment-plates being connected with the draft-sills by means embracing a guide-groove on one part and a flange on the 65 other part, adapted for interlocking connection when the abutment-plates are in their normal or working positions and for discon-

nection when said plates are thrown out of said normal or working positions.

2. A draft-rigging comprising draft-sills, 70 draft-irons secured to said sills and provided with inwardly-facing shoulders, a draw-bar, a coiled draw-bar spring, spring follower-plates located one at each end of said draw-bar spring, and endwise-sliding abutment-75 plates located between the ends of said follower-plates, said draft-irons and abutment-plates being provided with guide-grooves and flanges adapted for interlocking engagement when the abutment-plates are in their normal 80 positions and for disconnection when the said plates are swung away from the draft-irons.

3. A draft-rigging comprising draft-sills, 85 recessed draft-irons secured to said sills, and endwise-sliding abutment-plates mounted on the draft-irons, each of said draft-irons being provided on one of its edges with a flange-like projection provided with a guide-groove and the abutment-plates being provided with 90 laterally-projecting flanges adapted to engage and slide in said guide-grooves.

4. A draft-rigging comprising draft-sills, recessed draft-irons provided with inwardly-facing shoulders, and sliding abutment-plates 95 mounted on said draft-irons, each of said abutment-plates having a sliding interlocking connection with the draft-irons on which it is mounted, embracing a flange-like projection of curved form on one edge of the 100 draft-iron, said projection being provided with a guide-groove and a curved flange on the corresponding edge of the abutment-plate adapted to engage said guide-groove.

5. A draft-rigging comprising draft-sills, 105 draft-irons attached to said sills and provided with detachable supporting-strips detachably secured to the lower edges thereof and abutment-plates having sliding interlocking engagement at their upper edges with the draft-irons by means of projections on said upper edges of the draft-irons shaped to form guide-grooves, and flanges on the upper edges of the draft-irons adapted to engage said guide-grooves, said supporting-strips being adapted 110 to engage the lower edges of said abutment-plates to hold the same in operative position.

6. A draft-rigging comprising draft-sills, recessed draft-irons secured to said sills, and follower-plates located in the recesses of the 115 draft-irons, and detachable strips forming the lower walls of said recesses, said abutment-plates having interlocking engagement at their upper edges with the draft-irons by means of grooved projections on the draft-irons and flanges on the abutment-plates, and said abutment-plates being provided at their lower edges with depending flanges which engage the inner edges of the said detachable strips.

7. A draft-rigging comprising draft-sills, 120 draft-irons secured to said sills, a draw-bar, a coiled draw-bar spring, spring follower-plates located one at each end of said draw-

bar spring and extending at their ends into the recesses of the draft-irons, said draft-irons being provided with detachable bottom strips and sliding follower-plates located within the recesses of the draft-irons and having sliding interlocking engagement at their upper edges with the said draft-irons and sliding engagement at their lower edges with said strips.

10 8. A draft-rigging comprising draft-sills provided with forwardly and rearwardly facing shoulders, a draw-bar, a coiled draw-bar spring, spring follower-plates located between each end of the draw-bar spring and the draw-bar, and having their ends separated from each other, the outermost of said spring-plates being adapted to act against the shoul-

ders on the draft-sills, longitudinally-sliding abutment-plates on the said draft-sills located between the ends of the innermost follower-plates and adapted to transmit pressure from one to the other of said innermost follower-plates, each of said abutment-plates having sliding and interlocking connection at one of its edges with its associated draft-sill.

In testimony that I claim the foregoing as my invention I affix my signature, in presence of two witnesses, this 5th day of August, A. D. 1901.

JAMES MILTON WAUGH.
